UNITED STATES PATENT OFFICE.

WILLIAM C. HUEBNER, OF CHICAGO, ILLINOIS.

PRINTING MACHINE.

Application filed May 28, 1928. Serial No. 281,184.

This invention relates to improvements in printing machines, and more particularly offset and letterpress uniting machines.

One object of the invention is to provide 5 a compact and efficient machine so arranged that direct impressions may be made from a flat printing surface of either relief, intaglio or planographic type, or offset impressions may be made from any of said kinds of 10 flat printing surfaces and transferred to a flat print-receiving surface composed of any suitable material.

Another object of the invention is to provide 15 a printing machine having the characteristics indicated in the preceding paragraph and wherein the impressions taken or transferred are made through the aid of pressure means so constructed and operated as to eliminate any tendency of the impressions 20 to be distorted during the making thereof.

Other objects are to provide a printing machine which is constructed to permit the 25 various printing and print-receiving surfaces to be disposed flatwise in opposition to each other and held from relative movement in or parallel with the printing plane during all of the operations of transferring and printing from one surface to the other; 30 also to provide a machine having a movable support or platen for the primary printing surface and a swinging frame or support on which a resilient offset or transfer blanket or element may be stretched flat, and which 35 is movable toward and from the primary printing surface so as to permit the transfer element to be pressed into face to face contact therewith for receiving a print therefrom; also to provide pressure means expeditiously movable into and out of operative 40 relation to the contacting transfer and primary printing elements for affording the required pressure to enable the image to be transferred from one surface to the other; 45 also to provide a support or table for the final print-receiving element, or proof sheet, which is movable with said proof sheet or element thereon to a position over the aforesaid platen and to mount said swinging 50 frame so that the same may be moved into

operative position over said table to permit the image on said transfer element to be printed on said sheet or print-receiving element.

Further objects are to provide an offset 55 printing machine or proof press in which the aforementioned platen, swing frame, pressure means and proof sheet support have means for adjusting the various elements carried thereby so that these elements may 60 be placed at different elevations as the various steps of the work proceed; also to construct a machine of this kind having means for placing the platen or primary printing 65 element support accurately in predetermined position and for measuring and indicating the movements of said platen; also to mount said proof sheet support in a manner to permit the same to be easily moved into and out of operative position over the platen 70 and to provide the same with means for permitting the support to have clearance relative to the supports for the other elements during such movements, said means also permitting the table to be lowered into 75 an operative position; also to provide novel pressure means for effecting close contact between the various printing and print-receiving surfaces, and means including a carriage movable to and from a position over 80 said platen; also to provide means for supporting a pressure roller on said carriage and to permit the roller to be operatively positioned at various predetermined elevations for use in various stages of printing 85 on the machine; also to provide means for detachably mounting rollers of different widths thereon for use in connection with work of different dimensions, and to improve pressure means for machines of this 90 sort in various other respects hereinafter set forth; also to provide means for adjustably supporting the transfer element swing frame in position for giving ready access for attaching the transfer elements thereto or detaching them therefrom, and to provide 95 means for supporting the swing frame in an intermediate position; and also to provide a hinge connection between said frame and the base of the machine which permits said 100

frame to be readily moved to and from operative position; also to provide means whereby the hinge structure as a whole may be adjusted relatively to said base to permit the transfer element on the frame to extend in different operative planes, in accordance with the work in hand; and also to improve and simplify machines of the character stated in the other respects hereinafter described and set forth in the claims.

In the accompanying drawings:

Fig. 1 is an elevation of the front side of an offset printing machine or proof press embodying my invention.

Fig. 2 is a fragmentary, sectional plan view of a portion of the pressure roller carriage, on an enlarged scale, on line 2—2, Fig. 8.

Fig. 3 is a vertical section of one of the adjustable brackets for supporting the pressure rolls on line 3—3, Fig. 9.

Fig. 4 is a fragmentary plan view of the machine with portions broken away.

Fig. 5 is a fragmentary face view of a portion of the swing frame for the transfer element on an enlarged scale, showing the adjustable means for mounting and stretching said element thereon.

Fig. 6 is an enlarged detail section of the gripping means for the transfer element.

Fig. 7 is a transverse, vertical section, on an enlarged scale, of the machine, on line 7—7, Fig. 1, showing the pressure roller supporting carriage.

Fig. 8 is a side elevation, partly in section, of said carriage.

Fig. 9 is a fragmentary, vertical, transverse section of said carriage, on line 9—9, Fig. 8.

Fig. 10 is a longitudinal section of the carriage and an adjacent portion of the machine showing in part the proof sheet supporting table and the swinging transfer frame and transfer element in operative relation thereto, on line 10—10, Fig. 7.

Fig. 11 is a longitudinal, vertical section of a portion of the pressure roller carriage on line 11—11, Fig. 2.

Fig. 12 is a similar view on line 12—12, Fig. 7.

Fig. 13 is a fragmentary, longitudinal section through the platen which supports the primary printing element showing the intermediate transfer element supported on its swing frame in operative relation to said primary printing element.

Fig. 14 is a fragmentary plan view, partly in section, of the platen and its operating mechanism.

Fig. 15 is a perspective view of a portion of said operating mechanism.

Fig. 16 is a plan view, partly broken away, of the movable table for supporting the print-receiving surface or proof sheet.

Fig. 17 is a side elevation thereof, partly broken away.

Figs. 18 and 19 are fragmentary, transverse sections thereof, on an enlarged scale on line 18—18, Fig. 17, showing the parts in two different positions.

Fig. 20 is a transverse, vertical section of the transfer element swing frame and the adjusting and operating means therefor.

Fig. 21 is a longitudinal section of the platen, proof sheet supporting table and swing frame in operative relation for transferring an image from the transfer element to a proof sheet.

Fig. 22 is a transverse section taken at right angles to Fig. 21, with the parts in similar relation, and showing a pressure roller and portions of the roller carriage in operative relation thereto.

Fig. 23 is an enlarged, vertical section on line 23—23, Fig. 14, of part of the adjusting means for the platen.

Fig. 24 is a fragmentary plan view showing means for locking the proof sheet supporting table in operative or printing position.

Fig. 25 is a face view thereof.

Fig. 26 is a longitudinal, vertical section thereof on line 26—26, Fig. 25.

Fig. 27 is a face view of the holding means for preventing lateral displacement between the swinging frame, proof sheet supporting table and platen when these parts are in printing relation.

Fig. 28 is a longitudinal, vertical section thereof on line 28—28, Fig. 27.

Fig. 29 is a transverse section of a locking device for supporting the swing frame rigidly in holding position.

Fig. 30 is a vertical section thereof on line 30—30, Fig. 29.

In its general organization, the improved offset printing machine or proof press in the form illustrated in the drawings, comprises a base frame or pedestal 10 upon which is operatively arranged a platen A for supporting any suitable or desired primary printing element, such as a glass negative, thin plate, lithographic stone or the like, and a proof sheet supporting table B and a roller carriage C mounted on suitable tracks secured to the base for horizontal movement to and from a position over the platen. At the opposite side of the platen a swing frame D is hinged. On this swing frame a suitable transfer element, such as a rubber blanket, is stretched flat and taut, and the swing frame is so mounted that said transfer element can be moved into face to face contact with the primary printing element, the pressure roller on the carriage C being movable over the contacting elements for exerting pressure on and securing close contact between the same for transferring the image to the transfer element. The pressure roller

carriage C is now moved to one side, the transfer member swung away from its position over the platen, the table B passed beneath the carriage C to position over said platen, a proof sheet or other print-receiving element placed on the table B, and the swing frame D is again lowered so as to bring the transfer member thereon into face to face contact with said proof sheet. The pressure roller carriage C is then moved again to a position over the platen so as to exert pressure on and effect a close contact between said transfer element and said proof sheet for transferring the image to said proof sheet.

The base of pedestal 10 is preferably in the form of a hollow casting having at its upper end an enlarged head or portion 11 forming an upwardly opening, rectangular recess 12 bounded by opposite side walls 13 and end walls 14. The platen A, which is preferably in the form of a reinforced plate having a flat, horizontal top face α is disposed within and conforms to the shape of the recess 12. Fixed to the outer side of each wall 13 of the base is a longitudinally extending horizontal track rail 15. The top edges of these rails 15 and of the walls 13 and 14 are finished flush and extend in what will hereinafter be termed the primary printing or image transferring plane, designated $x-x$, see Figs. 4, 10 and 21.

The platen A is adapted to support on its surface different primary printing elements such as glass negatives, lithographic stones and the like, designated at X, Fig. 13, which may vary in thickness, with the printing face X' of the selected element lying in the primary printing plane. To permit this, the platen is adjustable vertically relative to the base 10 by suitable means.

The means shown for this purpose includes four lifting screws or threaded shafts 16, one of which is secured in and depends from each corner of said platen A, and is normally prevented from endwise movements relatively to said platen by shoulders or collars 17 and 18, and from rotation by a nut or sleeve 19, see Figs. 4 and 23. The lower ends of the screw shafts 16 extend and operatively engage in internally threaded, rotatable sleeves 20, each of which passes downwardly through a hole in the bottom wall 21 of the head 11, and through a bearing bracket 22 secured to the underside of said wall, and has fixed to its lower end a spiral gear 23. The sleeve is prevented from endwise movement by a shoulder 24 at its upper end which bears on a ball bearing 25 seated in the wall 21, and a nut 26 threaded on its lower end and engaging the spiral gear 23, which at the same time clamps the gear in place against the bracket 22. One pair of the gears 23 mesh with spiral gears 27 fixed on a horizontal shaft 28, while the other pair of gears 23 mesh with correspond-

ing gears 27 on a second horizontal shaft 28. The shafts 28 extend longitudinally of the machine and rotate in the bearings 22.

Intermediate of its ends, each shaft 28 is provided with a fixed spiral gear 29 which meshes with a corresponding gear 30 fixed on a transverse horizontal drive shaft 31 journaled to rotate in brackets 32 depending from the bottom wall 21 of the head 11. The front end of said shaft 31 is provided with a crank 33 for turning it. It will be seen that by appropriate rotation of said shaft, simultaneous rotation of all the sleeves 20 is effected, thus elevating or lowering the screws 16 and the platen A.

While, as before stated, the lifting screws 16 are normally prevented from rotation, said screws can be individually rotated for adjustment in an endwise direction relatively to their sleeves 20 and spiral gears 23 for initially levelling the surface α of the platen A when the parts are assembled, so that this surface will lie exactly in the aforesaid primary printing plane $x-x$. These means include the aforementioned nut 19 which is keyed on the upper end of the lifting screw 16 and engages between the collar 18 and the bottom of a pocket 30 formed in the top of the platen. The nut 19 has an annular series of holes 37 extending therethrough and another series of similar holes 38 is formed in the bottom wall of said pocket. The holes 37 and 38 are located on different centers so that one series has, for example, one hole more or less than the other. A stud 39 extending through two corresponding or registering holes 37 and 38 prevents the screw 16 from rotating, but by removing the stud and turning the nut 19, the screw 16 can be rotated and the adjacent portion 100 of the platen will be raised or lowered relatively to the corresponding sleeve 20. When the platen has been properly levelled, the stud 39 is inserted into that pair of holes 37 and 38 which happens to be in register. 105 The foregoing affords a fine and very accurate adjustment for levelling the platen A.

Means are preferably provided for measuring the movements of the platen A so that it can be raised or lowered predetermined required distances in accordance with the thickness of different primary elements X, for placing the image bearing face thereof in the plane $x-x$ and so that the exact adjustment for any particular element can be recorded for future use.

In the construction shown, see Figs. 1, 7, 14 and 15, a part of the front horizontal shaft 28 is provided with a screw thread 125 40 of say, ten threads per inch. A travelling nut or finger 41 has threaded engagement with the screw part 40 and extends forwardly and slidingly embraces a horizontal scale bar 42 extending between and fixed to the 130

adjacent bearings 22 and 32. The scale bar is graduated, for example, in inches, and a scribed line or pointer 43 on the sliding finger 41 cooperates with these graduations. 5 The drive shaft 31 has fixed on its front end a disk or dial 45 having peripheral graduations 46 representing one hundred equal parts and which, in the rotation of said shaft, move past a fixed pointer 47 on the pedestal 10. The threads of the lifting screws 16 preferably correspond to those of the screw 40 of the shaft 38, so that when the shaft 31 is turned, each revolution thereof will shift the platen one tenth of an inch. 10 15 Therefore, the movements of the platen are indicated by the dial 45 and pointer 47 in tenths, hundredths and thousandths, while full inch measurements are indicated by the movements of the finger 41 along the scale bar 42.

Each track rail 15 is provided adjacent its inner top edge with a longitudinal guide groove or track 50 and outwardly beyond these grooves there is an overhanging horizontal rack bar 51 extending parallel with the grooves 50 and having its teeth extending upwards. Spaced below and parallel with the rack bars at each side of the machine, the rails 15 are provided with horizontal ledges or tracks 52.

The aforementioned table B see Figs. 16-19, is formed of a flat, horizontal plate 53, preferably of thick glass, supported on a suitable rectangular frame disposed above and extending between the track rails 15. Rollers or wheels 55 journalled at each corner of said frame and having flanges 55^a engaging in the guide grooves 50 permit the table B to be readily moved lengthwise of the machine from one end to the other. The side members 56 and end members 57 of the table frame are preferably of angular cross section, and the plate 53 is detachably secured upon the bottom flanges of said members by clips or blocks 58. The side and end members 56 and 57 of the table are preferably made of the same length as the side and end walls 13 and 14 respectively of the pedestal head 11, for a purpose to be later explained.

The table B is adapted to be supported on the tracks 15 at two different elevations, an upper one in which the frame can be moved freely along the tracks 51 clear of the walls 55 of the head 11 to a position over the platen A, and a second or lower elevation, in which the bottom face of the frame is substantially in the plane $x-x$ and so as to rest on the top of the pedestal head 11 and face a of the platen A with the top face of the plate 53 in a final printing or image transferring plane $y-y$, Figs. 10, 18 and 21. For this purpose, each pair of rollers 55 is eccentrically mounted on a transverse shaft or journal 60 bearing in holes 61 in the opposite

side members 56 and in brackets 62 fixed to the frame. The ends of each shaft 60 have eccentric disks 63 thereon each of which is received in a cavity in the corresponding roller 55. The shafts are provided near their opposite ends with fixed pinions 65. The pinions at each side of the frame mesh with corresponding horizontal, longitudinal rack bars 66 slidably mounted for endwise movement on the adjacent frame member 56. A horizontal shaft 67 journalled in one of said frame members 56 has a crank 68 on one end and a pinion 69 on the other. The pinion 69 meshes with the adjacent rack bar 66 so that by swinging the crank the racks are shifted to rotate the shafts 60, the movements of the crank 68 being limited by stop pins 70 on the frame B. The parts are so proportioned and related that when the crank is engaging the left hand pin 70, Fig. 17, the table is in its lower position, while when the crank is moved into engagement with the other pin 70, the table will be raised by means of the eccentrics, as in Figs. 1 and 19. In the latter position the table B is freely movable lengthwise of the tracks 15.

The swing frame D, which is preferably in the form of a rectangular frame of substantially the same horizontal dimensions as that of the pedestal head 11, is hinged to swing about a transverse, horizontal axis disposed adjacent the right hand transverse wall 14 of the pedestal, see Fig. 1 and movable to three different positions. In one of these positions, the swing frame occupies the substantially horizontal or recumbent, outwardly extending position shown in Figs. 1 and 4, to permit a rubber blanket or other transfer element d to be detachably secured and stretched taut thereon and facing upwardly. The swing frame can also be swung to a second recumbent position extending horizontally inwards over the platen A with the blanket d facing downwards and lying either in the plane $x-x$ and in contact with the face of the primary printing element a to receive an impression therefrom, or in the plane $y-y$ to transfer said impression to a proof sheet or other element supported on the table B, and finally the swing frame D can be supported in an inoperative, upwardly extending position, see Fig. 1, to which it is moved temporarily, for example, during the removal of one proof sheet and the positioning of another, as when making several impressions from one subject, or for other purposes.

The swing frame D consists of a pair of spaced parallel side members 71 rigidly connected by transverse end members 72. The blanket d can be secured to and stretched on the swing frame in any suitable way. As shown in Figs. 4 and 5, the opposite ends of the blanket are inserted between pairs of

adjustable gripper bars 73 and 74, one pair of which is mounted on each of the cross members 72. After an edge of the blanket has been inserted between a pair of said bars, said edge is clamped tightly between the latter by means of a plurality of screws 75 which extend through holes in the bars 74 with their heads bearing against these bars, said screws having threaded engagement in tapped holes in the other bar 73. After the two opposite edges of the blanket have been thus clamped, each pair of bars is moved in a direction away from the other pair to draw the transfer blanket *d* taut, as by adjusting screws or bolts 76 which extend through holes in a flange or part 77 of the adjacent frame bar 72 and engage in threaded holes in the bar 74. By this construction, a transfer blanket can readily be mounted, face up on the swing frame D, when the latter is in the outwardly extending position, Fig. 4, or one blanket can be expeditiously substituted for another.

One of the end members 72 of the swing frame has a projecting web 78 on which is a pair of spaced hinge blocks 79. These blocks are connected by transverse, horizontal hinge pins 80 to a pair of bearing bosses 81 extending upwardly from spaced brackets 82 projecting from a vertical, transverse slide or plate 83. This slide is disposed between the tracks 15 and is movable in vertical guides 83^a fixed to the outer face of the adjacent wall 14 of the pedestal head 11. Each bracket 82 is provided below the hinges 80 with a vertical rack 84, and meshing with these racks are two pinions 84^a fixed on a transverse, horizontal operating shaft 85 journalled in bearing brackets 86 depending from the track rails 15. The shaft is provided with a crank 87 for turning it, and by appropriate rotation thereof, it will be apparent that the axis of the hinge 80 about which the swing frame D rotates may be raised or lowered.

In order to support the swing frame D at the desired elevation to which it has been moved by the operating shaft 85 for locating the transfer blanket *d* in the plane *x*—*x* or *y*—*y*, adjustable locking or holding means are provided. The means shown for this purpose comprises a pair of horizontally movable bolts 90, one of which is arranged for sliding movements in a cavity 91 in each of the brackets 82. Fixed locking plates 92 on the adjacent end wall 14 of the pedestal head are provided at appropriate elevations with holes 94, in either of which the bolts 90 are adapted to enter when the sliding plate 83 and its connected brackets 82 and swing frame D are moved as above described. For simultaneously actuating the bolts 90, a lock shaft 96 journalled in bearings 97 on the brackets 82 and having pinions 98 meshing with rack teeth 99

on said bolts is provided. A handle 100 on one end of said shaft 96 permits the shaft to be rotated for projecting the bolts into or retracting them from the holes 94.

When it is desired, for example, to transfer an image from the stone or other primary printing surface X to the surface of the transfer blanket *b*, said member X is placed upon the platen A and it is inked up. The platen is adjusted so as to place the printing face of the element X in the plane *x*—*x*. The operating shaft 85 is then turned by means of the crank 87 until the bolts 90 are opposite the lower pair of holes 94 in the fixed slide plate 92. The lock shaft 96 is next actuated to project the bolts 90 into these holes 94. The axis of the swing frame hinge 80 is now in such position that when swung about the latter to a recumbent position above the platen A, the face of the transfer blanket will also lie in the plane *x*—*x*, in contact with the printing face of the element X. The inked image is now transferred to the surface of the element *d* by moving the roller carriage C to a position above the contacting elements and its pressure roller *c* moved into contact with and rolled over the back of the transfer element. The roller carriage is then moved away and the swing frame swung to the intermediate upwardly extending position shown in Fig. 1, and the element X removed from the platen.

The proof sheet supporting table B is then moved along the tracks 15 to a position over the platen, as shown in Figs. 21 and 22, and a suitable proof sheet or other final print-receiving element is placed thereon so that its print-receiving face lies in the aforesaid plane *y*—*y*. The locking bolts 90 are now retracted and the swing frame D elevated by turning the operating shaft 85 until the bolts 90 are located opposite the upper pair of holes 94, and the bolts 90 projected into said holes to rigidly support the swing frame. The pivotal axis 80 of the swing frame is now at such an elevation that when the latter is again moved to a recumbent position over the platen, the transfer element *d* with the transferred image thereon, is brought into the plane *y*—*y* and in contact with the face of the proof sheet. The roller carriage C is again moved to a position over the platen and its roller *c* passed again over the back of the transfer element to make the print upon the proof sheet. The pressure roller *c* is adjustable vertically to different elevations, as required for the foregoing operations, as will be later described.

The roller carriage C comprises a pair of upright side members 101 which are preferably in the form of castings connected by suitable tie rods 102 and a cross bar or bridge member 103. These side members

101 are disposed outwardly alongside the respective rails 15 of the machine and each is provided on its inner face with a pair of rollers 104 extending between and in contact with the upper face of the track bar 52 and the lower face of the rack bar 51. By this means the carriage is supported for travelling movements without vertical displacement. For actuating the carriage, an 10 operating shaft 105 is provided, and which extends transversely across the machine and is journaled at each end in a gear box 106 on each of said members, within which it is provided with a spur gear 107. This gear 15 meshes with an idler 108 which in turn meshes with a driving gear 109 secured on a stud shaft 110 which projects through the side member and is provided upwardly beyond said member with a pinion 111 meshing with the adjacent rack bar 51. The operating shaft 105 is provided with a suitable crank 111a.

The cross bar or bridge 103, see Figs. 3, 7 and 9, is preferably in the form of a casting of substantially U shaped cross section and is constructed to support pressure rollers *c* of different lengths for use in connection with transfer blankets of different widths. The rollers *c* are supported beneath the bridge 103 by means of a pair of transversely adjustable brackets 112 depending from said bridge. Each bracket has a boss or journal portion 113 within a cavity 114 in which a ball bearing is mounted. 25 The roller *c* has at each end a journal or pintle adapted to-rotatably fit in the bearings of the brackets 112. The bridge 103 is provided with horizontal guide grooves 115 on each face, into which locking studs 116 30 projecting inwardly from the upwardly extending parts 117 of the bracket enter. The parts 117 are provided with inwardly directed shoulders 118, see Fig. 3, which rest on corresponding shoulders 119 of the bridge 40 103 for supporting the bearings. By loosening the studs 116, the bearings can be moved toward or from each other to receive rollers *c* of different lengths, and after the appropriate roller has been properly positioned, the studs 116 are screwed tightly into 45 the guide grooves 115, thereby holding the roller brackets rigidly in place. If desired, the bridge member 103 may be provided with means for engagement with the 50 intermediate portions of relatively long rollers *c* so as to prevent flexing of such rollers between their ends when in operation and resulting in uneven pressure and consequent 55 improper transfer of the images.

60 These means, see Figs. 7 and 10, comprise a pair of auxiliary rollers 120 mounted in a vertically adjustable yoke 121 which extends beneath and straddles the brace 103 and is provided with parts at opposite sides 65 which enter corresponding guide recesses

122 therein. An adjusting screw 123 extends vertically through the brace and is mounted for rotation therein while being prevented from endwise movements relatively thereto by upper and lower collars 124 engaging the bridge piece. The screw 123 has a depending threaded portion 125 engaging in a tapped hole in the yoke 121, enabling the yoke to be raised or lowered by turning the screw to cause the rollers 120 to bear on the roller *c* with appropriate pressure sufficient to prevent the latter from flexing in use. Any other suitable means may be provided for this purpose.

In order to permit the rollers *c* to be movable to operative positions in the planes *x*-*x* and *y*-*y* and also to a still higher clearance position to permit the same to clear the table B and swing frame D, during the travel of the carriage to and from its position over the platen A, the brace or bridge member 103 is adjustably supported at each end in a slide 126 which in turn slidably engages in a vertical slot or opening 127 in the adjacent side member 101. As shown in Figs. 2, 9 and 11, each slide 126 comprises a pair of spaced, vertical blocks 128 bearing against opposite faces of a reduced projecting tongue portion 129 formed on the ends of the bridge 103. The blocks have shoulders at their inner sides engaging one face of the upright 103 while their outer sides are connected by a bracket or plate 130 which in turn embraces the outer face of said upright. Secured to the top of each slide 126 is a bearing 131 in which is rotatably mounted a vertical shaft 132 which is prevented from lengthwise movements in the bearing by means of collars 133 and is provided with a screw threaded lower portion 134 which enters a tapped hole in the tongue 129 of the bridge 103, thereby supporting the bridge in operative relation to the slide 126. Each bracket 130 extends laterally relative to the bridge 103 and is provided with a bearing 135 through which a horizontal, transverse shaft 136 extends. The shaft is provided with a pair of pinions 137 which mesh with fixed vertical racks 138, one of which is fixed on each side member 101. By rotating the shaft 136, as by means of a crank 139, the slides 126 and the cross bar or bridge 103 can be raised or lowered.

In order to support these parts at the different desired elevations, each slide 126 is provided with a horizontally movable bolt 140, similar to the bolts 90 for the swing frame D, and which is adapted to enter any one of a series of three vertically spaced holes 141 formed in a plate 142 fixed to the adjacent side member 101 of the carriage. The bolts may be projected into or retracted from the holes by means of pinions 143 meshing with rack teeth 144 on the bolts, 130

see Figs. 7 and 12. The two pinions 143 are mounted on a rock shaft 146 journalled in the extension of the bracket 130, and the shaft is actuated by a suitable rock arm or lever 147 on one end thereof. The described construction of the roller carriage C permits the proof sheet supporting table B to pass beneath the roller c and between the side members 101 without interference, while said carriage can pass over the superimposed swing frame D and table B, during the printing and transferring operations.

While the foregoing adjustments permit the rollers c to be elevated or lowered by vertical movements of the supporting bridge 103, it is desirable, when the parts are initially assembled, to provide means whereby the bridge 103 can be adjusted vertically relative to its supporting slides 126 so that when these slides are locked to the uprights 101 in the various positions described, the rollers, when brought into operative relation to the printing surfaces will be correctly positioned to afford appropriate pressure. For this purpose, the vertical shafts 132 are rotatably mounted in their bearings 131 and connected for simultaneous operation by suitable means. The means shown comprise a spiral gear 150 splined to each of the shafts 132 and prevented from endwise movements in the bearing 131 by spacing washers 151. A transverse horizontal shaft 152 journalled at each end of the bearing 131 is provided with spiral gears 153 meshing with the spiral gears 150 so that by rotating the shaft 152, both of the vertical shafts 132 will be rotated and these shafts, by their screw connections with the ends of the brace 103, will cause the same to be elevated or lowered in and relative to its slides 126. This feature can also be used in conjunction with the adjustable rollers 120 to exert additional pressure of the roller c on the printing or transfer elements, if required.

If desired, tension springs 154 connected to the bridge 103 and to pins on the slides 126 may be provided for counterbalancing the bridge and its attached roller to permit easier actuation of the same.

Any suitable means can be provided for supporting the swing frame D in its outwardly extending, recumbent position, and in its intermediate, upwardly extending position. The means shown in the drawings for this purpose includes a pair of spaced, horizontal arms 160, one of which is rigidly secured to each of the brackets 82 and extends longitudinally outwards. The outer ends of these arms are rigidly connected by a cross brace 161.

Extending transversely through and keyed to the arms 160 is a horizontal rod 162. A rest 163 is mounted on said rod so as to swing thereon from the horizontal swing

frame supporting position shown in full lines in Fig. 1, to an inclined position shown in dotted lines in said figure for supporting the frame in its intermediate position. This rest comprises a pair of arms 164, see Figs. 1 and 4, each having one end pivoted on said rod 163 adjacent the outer faces of the respective arms 160 and connected at their free ends by a transverse cross bar 165, the ends of which are extended so as to project into the path of the side members 71 of the swing frame D. In the position shown in Figs. 1 and 4, the arms 164 extend horizontally and rest on pins 166 projecting from the fixed arms 160. When the swing frame is swung downwardly and outwardly, the side members 71 thereof will engage and be supported by the ends of the cross bar 165. In this position the gripper bars 73 and 74 can be easily manipulated for attaching and detaching the transfer blankets on the swing frame.

The pivoted ends of the brace arms 164 are confined between the arms 160 and fixed collars 167 on the rod 163. One end of the rod 163 is extended at 168, Fig. 29. A sleeve 169 surrounds the extension and has a limited endwise movement thereon between the adjacent collar 167 and a second collar 170 on the end of the extension. This sleeve is keyed on or otherwise prevented from rotation about the rod 163 and its inner end has a pin or projection 171 thereon. By swinging the rest 162 about the rod 163 to the inclined position, Figs. 1, 29 and 30, the sleeve 169, when moved inwardly along the rod 163 from the position shown in Fig. 29, will cause the pin 171 to project into a hole 172 in the adjacent arm of the bracket 162, thus releasably but rigidly holding the brace in position to support the swing frame in an inclined position, as when the latter is moved away from its image-receiving or transferring position. Projecting pins 173 on the arms 160 and engaging the ends of the arms 164 serve to relieve the strains on the pins 171 and assist in holding the rest 162 in its inclined position.

Holding means are preferably provided for guiding the table B to and holding the same in operative relation to the platen A when in printing position thereover so as to prevent longitudinal or lateral displacement of said table and consequent improper printing or transfer of the images. For this purpose, see Figs. 24-26, the right hand cross member 57 of the table has a fixed projecting lug 175 formed with a pair of lateral stop portions 176. A stud 177 is arranged for limited vertical sliding movements in a hole 178 in said lug, and has a depending, reduced part 179 which is registrable with and fits into a hole 180 in a fixed lug 181 on the adjacent wall 14 of the pedestal head 11 by a downward movement of the stud. When the stud 177 is retracted its part 179 is drawn within the hole 178 and permits free longitudi-

dinal movements of the table. As the table B is moved to printing position, the lug 175 passes between upright spaced parts 182 on the lug 181, and the table is arrested by the 5 engagement of the stops with the parts 182, the stud 177 being at the same time axially alined with the hole 178 in the lug 181.

At its opposite end the table has a lug 183 from which depends a pivoted finger 184. 10 This finger is adapted to enter and closely fit in a slot or recess 185 in a fixed lug 186 on the pedestal, see Figs. 27 and 28, thereby cooperating with the holding stud 177 by preventing lateral displacement of the table B. 15

The swing frame D is also prevented from lateral displacement at its free end when in printing position, by a fixed finger 187 depending from a lug 188 on the frame, said finger entering a slot in the lug 183 of the table B. The top face of the lug 183 and the bottom face of the lug 188 abut and lie in the plane y—y and as the table when in lower, operative position rests on the top of the 20 pedestal, the swing frame will in turn be firmly supported in operative position.

By employing an open frame D and resilient sheet d stretched taut thereon so that the back side of the element d is accessible 30 (and which frame D and element d may collectively be called a "tympan") I am enabled to take impressions, either direct or offset, from those printing plates or surfaces which heretofore have involved a great deal of time 35 in the so-called "make-ready," very much faster, with less labor and time. Instead of utilizing make-ready beneath the printing plate, such as a copper plate, my improved tympan is brought down over the printing 40 plate and such thin sheets of paper or the like as may be necessary to produce the even impression, are placed on the upper or back side of the element d and when this is done, a light metallic plate is placed on top thereof, after which the pressure roller may be 45 moved over the tympan and the impression made.

Further, by employing a resilient tympan element in a flat condition, having a bodily 50 movable pressure roller cooperable therewith, all of the disadvantages of distortion of the impressions heretofore common in cylindrical offset rollers, are avoided.

I claim as my invention:

1. In an offset printing machine, the 55 combination of a primary printing surface, a platen for supporting said surface, a transfer element, a support on which said element is supported flatwise, said platen 60 and support being relatively movable to place said primary printing surface and said transfer element into face to face contact for transferring an image from the former to the latter, means for supporting a print 65 receiving element over said platen, and said

transfer element support being movable to a position over said supporting means for the print receiving element for transferring the image on said transfer element to said print receiving element. 70

2. In an offset printing machine, the combination of a primary printing surface, a platen for supporting said surface, a transfer element, a support on which said element is supported flatwise, said support being 75 movable to place said primary printing surface and said transfer element into face to face contact for transferring an image from the former to the latter, means for rigidly supporting a print receiving element over 80 the primary printing surface, and said transfer element support being movable to a position over said supporting means for the print receiving element for transferring the image on said transfer element to said 85 print receiving element. 90

3. In an offset printing machine, the combination of a primary printing surface, a platen for supporting said surface in an image transferring plane, a transfer element, a support on which said element is mounted flatwise, a hinge on which said support is mounted to swing to place said element parallel to said transferring plane with its face in contact with said printing surface for receiving an image from the latter, means for supporting a print receiving element in a final printing plane, and means for shifting said hinge to permit said transfer element support to swing to place said transfer element parallel to said latter plane and in contact with said print receiving element for transferring the image on said element to said print receiving element. 95

4. In an offset printing machine, the combination of a primary printing surface, a platen for supporting said surface in an image transferring plane, a transfer element, a frame on which said element is stretched taut and flat, a table mounted to move to a position over said platen to support a print receiving element in a final printing plane parallel to said other plane, and a hinge on which said frame is mounted to place said transfer element in said first plane in contact with said primary printing surface to receive an impression therefrom, said hinge being adjustable to enable said transfer element to swing into said second plane in contact with said print receiving element for transferring the image on said transfer element to said print receiving element. 100

5. In an offset printing machine, the combination of a base, a platen thereon on which a primary printing element is rigidly supported in a print transferring plane, a transfer element movable into contact with said printing element to receive an impression therefrom, means for adjusting said platen 115 towards and from said transferring plane to 120

125 130

- place the image bearing faces of primary printing elements of different thickness in said plane, said adjusting means comprising a plurality of lifting screws carried by said 5 platen, sleeves rotatable in said base and prevented from endwise movements relative thereto and which have threaded engagement with said lifting screws, a drive shaft, shafts operatively connecting said drive 10 shaft and said sleeves for effecting simultaneous rotation thereof when said drive shaft is rotated to impart endwise movements to said lifting screws, and means for indicating the adjustments of said platen, said means 15 comprising a threaded portion on one of said shafts, a fixed graduated scale bar on said base, and a member operatively engaging a threaded portion of said shaft so as to move along the same upon rotation of the latter, 20 and said member having a part which moves past the graduations on said scale bar to indicate the travel of said member and movement of said platen.
6. In an offset printing machine, the combination of a base, a platen thereon on which a primary printing element is rigidly supported in a print transferring plane, a transfer element movable into contact with said printing element to receive an impression therefrom, means for adjusting said 25 platen towards and from said transferring plane to place the image bearing faces of primary printing elements of different thickness in said plane, said adjusting means comprising a plurality of lifting screws carried by said platen, sleeves rotatable in said base and prevented from endwise movements relative thereto and which have threaded engagement with said lifting screws, a drive 30 shaft, a driven shaft operatively connecting said drive shaft and said sleeves for effecting a simultaneous rotation thereof when said drive shaft is rotated to impart endwise movements to said lifting screws, 35 and means for measuring and indicating the adjustments of said platen, said means comprising a threaded portion on one of said shafts, a fixed scale bar graduated in units of measure, a member mounted on and movable along said threaded portion upon rotation of said shaft, said member having a part movable past the graduations on said scale to indicate the adjustment of said platen in said units of measure, and a second 40 member graduated in fractions of said unit of measure fixed on said other shaft and movable past a stationary part on said base to indicate the adjustments of said platen in fractions of said units of measure.
- 45 7. In an offset printing machine, the combination of a platen for supporting a primary printing element in a predetermined printing plane, a table for rigidly supporting a print receiving element flatwise, said table being movable to a position over said 50 platen for placing the face of said element in a second predetermined printing plane, and a transfer element mounted flatwise and which is movable consecutively into said different printing planes for receiving an image from said primary printing element and transferring the same to said print receiving element.
8. In an offset printing machine, the combination of a base, a platen movable thereon for supporting a primary printing element flatwise with its printing face in a predetermined printing plane, tracks on said base extending parallel with said plane, a table movably supported on said tracks to travel thereon, said table having a face for supporting a print receiving element flatwise in a second predetermined printing plane disposed above said platen, a transfer element, and a support on which the latter is mounted flatwise, said support being adjustably supported on said base so as to position said transfer element in either of said printing planes and in face to face contact with said printing element of print receiving element.
9. In an offset printing machine, the combination of a platen for supporting a primary printing element in a predetermined printing plane, a table for rigidly supporting a print receiving element flatwise, said table being movable to a position over said platen for placing the face of said element in a second predetermined printing plane, a transfer element mounted flatwise and which is movable consecutively into said different printing planes for receiving an image from said primary printing element and transferring the same to said print receiving element, a pressure roller, and means for supporting the same over said platen at different elevations so as to engage said transfer element in either of said planes to afford printing contact between the same and either of said other elements.
10. In an offset printing machine, the combination of a base, a platen movable thereon for supporting a primary printing element flatwise with its printing face in a predetermined printing plane, tracks on said base extending parallel with said plane, a table movably supported on said tracks to travel thereon, said table having a face for supporting a print receiving element flatwise in a second predetermined printing plane disposed above said platen, a transfer element, a support on which the latter is mounted flatwise, said support being adjustably supported on said base so as to position said transfer element in either of said printing planes and in face to face contact with said printing element or print receiving element, and a carriage movable to a position over said platen and having means for supporting a pressure roller at

different elevations so as to engage said transfer element in either of said planes to afford printing contact between the same and either of said other elements.

- 5 11. In an offset printing machine, the
combination of a base, means for supporting
a printing element in a flat printing plane
disposed in predetermined relation to said
base, means for supporting a print receiving
10 element flatwise in a print receiving plane
disposed parallel to and above said first
plane, a transfer element, a member on
which the same is supported flatwise, a hinge
connection between said member and said
15 base to permit said member to swing from a
position at one side of said base to a position
over the same, and means for adjusting said
hinge connection relatively to said base to
permit said transfer element to extend in
20 either of said printing planes in contact
with the respective elements therein.

12. In an offset printing machine, the combination of a base, means for supporting a printing element in a flat printing plane disposed in predetermined relation to said base, means for supporting a print receiving element flatwise in a print receiving plane disposed parallel to and above said first plane, a transfer element, a member on 25 which the same is supported flatwise, a hinge connection between said member and said base to permit said member to swing from a position at one side of said base to a position over the same, means on said base for rigidly 30 supporting said member in said first position, with said transfer element facing upwards, means for supporting said member in an intermediate position, and means for adjusting said hinge connection relatively to 35 said base to permit said transfer element to extend in either of said printing planes in contact with the respective elements there-in.

- 45 13. In an offset printing machine, the
combination of a base, means for supporting
a printing element in a flat printing plane
disposed in predetermined relation to said
base, means for supporting a print receiving
element flatwise in a print receiving plane
disposed parallel to and above said first
50 plane, a transfer element, a member on
which the same is supported flatwise, a slide
mounted in guides on said base to move in a
direction perpendicular to said printing
planes, a hinge connection between said slide
55 and said member to permit the latter to be
moved to a position over said base with said
transfer element in parallel relation to said
printing planes, and means for adjusting
said slide to place said transfer element in
60 either of said printing planes in contact
with the respective elements therein.

14. In an offset printing machine, the combination of a base, means for supporting a printing element in a flat printing plane disposed in predetermined relation to said

base, means for supporting a print receiving element flatwise in a print receiving plane disposed parallel to and above said first plane, a transfer element, a member on which the same is supported flatwise, a slide 70 mounted in guides on said base to move in a direction perpendicular to said printing planes, a hinge connection between said slide and said member to permit the latter to be moved to a position over said base with said 75 transfer element in parallel relation to said printing planes, means on said base for adjusting said slide to place said transfer element in either of said printing planes, and means for locking said slide to said base in 80 either of its adjusted positions.

15. In an offset printing machine having means for supporting a printing element and a print receiving element flatwise in superimposed parallel printing planes, a transfer element adapted to rest flatwise upon one and then the other of said elements, a pressure roller, a carriage for supporting the same and which is movable to place said roller above and disposed in parallel relation to said printing planes, and adjustable means on said carriage for lowering said roller into either of said planes and engaging said transfer element, and means for guiding said carriage to permit said roller to travel over said transfer element and effect printing contact between the same and the element upon which it rests. 85 90 95

16. In an offset printing machine having
means for supporting a printing element 100
and a print receiving element flatwise in
superimposed parallel printing planes, a
transfer element adapted to rest flatwise
upon one and then the other of said ele-
ments, a pressure roller, a carriage for sup-
porting the same and which is movable to
place said roller into operative position
relative to said printing planes, means on
said carriage for raising or lowering said
roller to place the same into either of said
planes and engaging said transfer element,
means on said carriage for locking and
holding said roller in fixed relation to said
planes, and means for guiding said carriage
to permit said locked roller to travel over
said transfer element and effect printing
contact between the same and the element
upon which it rests. 110 115

17. In an offset printing machine having means for supporting a printing element and a print receiving element flatwise in superimposed parallel printing planes, a transfer element adapted to rest flatwise upon one and then the other of said elements, a pressure roller, a carriage for supporting the same, tracks for supporting and guiding said carriage for movement in a direction parallel with said printing planes, whereby said roller can be moved to an operative position over said elements and 130 125 120

- disposed in parallel relation to said planes, means on said carriage for raising and lowering said roller to place the same into either of said planes and engaging said transfer element so that said roller can travel over said element to effect printing contact between the same and the element upon which it rests, and means for shifting said roller to another position in which it will clear said supporting means for said printing and print receiving elements during the travel of said carriage to operative position. 18. In an offset printing machine having means for supporting a printing element and a print receiving element flatwise in superimposed parallel printing planes, a transfer element adapted to rest flatwise upon one and then the other of said elements, a pressure roller, a carriage for supporting the same, tracks for supporting and guiding said carriage for movement in a direction parallel with said printing planes, whereby said roller can be moved to an operative position over said elements and disposed in parallel relation to said planes, means on said carriage for raising and lowering said roller to place the same into either of said planes and engaging said transfer element so that said roller can travel over said element to effect printing contact between the same and the element upon which it rests, means for shifting said roller to another position in which it will clear said supporting means for said printing and print receiving elements during the travel of said carriage to operative position, means for initially adjusting said roller relative to said carriage and said tracks so that when moved into said printing planes it will effect a desired pressure on said contacting elements, and means for locking said roller when adjusted to either of the aforesaid positions. 19. In a machine of the character described, the combination with a flat platen support for a printing surface; of a tympan; a supporting table for a print-receiving surface; means for moving said table to superimposed relation with the platen support; adjustable means for moving the tympan over and in operative position with either said platen support or table; and pressure means cooperable with the tympan in either of its operative positions for effecting an impression. 20. In a machine of the character described, the combination with a flat platen support for a printing surface; of a tympan; a supporting table for a print-receiving surface; means for moving said table to superimposed relation with the platen support; adjustable means for moving the tympan over and in operative position with either said platen support or table; and a pressure roller cooperable with the tympan in either of its operative positions. 21. In a machine of the character described, the combination with a flat platen for a printing surface; of a flat table for a print-receiving surface; an open frame tympan having a resilient element in taut flat condition, said frame, platen and table being relatively movable whereby the tympan may be disposed in cooperative relation with both the platen and table; and a pressure roller operative on the back side of said resilient element to take an impression from the printing surface and to transfer an impression to the print-receiving surface. In witness that I claim the foregoing, I have hereunto subscribed my name this 23rd day of May, 1928.

WILLIAM C. HUEBNER.
